UNITED STATES PATENT OFFICE.

CLARENCE F. GILCHRIST, OF TOLEDO, OHIO, ASSIGNOR TO THE ELECTRIC AUTO-LITE COMPANY, OF TOLEDO, OHIO, A CORPORATION OF OHIO.

CURRENT CUT-OUT.

Application filed January 24, 1918. Serial No. 213,526.

To all whom it may concern:

Be it known that I, CLARENCE F. GILCHRIST, a citizen of the United States, residing at Toledo, in the county of Lucas and State of Ohio, have invented certain new and useful Improvements in Current Cut-Outs, of which I declare the following to be a full, clear, and exact description.

This invention relates to a type of current cut-out employed in connection with battery charging systems.

In electric systems such as are employed in motor vehicles and steam railroad cars, in which a storage battery in connection with a charging dynamo is utilized, it is necessary that means be provided for the prevention of the discharge of the battery through the dynamo when the latter is motionless or operating at low speeds with consequent low voltage. For this purpose, an electro-magnetic switch is commonly employed in the form of a reverse-current cut-out which has the additional function of preventing chattering of the contact points.

The principal object of this invention is to provide a cut-out of this above named type, which will have a quick break at the time of disconnection.

Another object is to provide a switch with a magnetic circuit of relatively small structural dimensions, but so arranged as to remain unsaturated at all generator voltages below that at which the device is intended to operate.

Further objects, and objects relating to economies of manufacture and details of construction, will definitely appear from the detailed description to follow.

I accomplish the objects of my invention by the devices described in the following specification.

A structure constituting a preferred embodiment of my invention is illustrated in the accompanying drawings, forming a part of this specification, in which—

Fig. I is a plan view of a structure embodying my invention.

Fig. II is a vertical section through the device taken on the line II—II of Fig. I.

Fig. III is an end view of the structure with the casing in section.

Fig. IV is a view of the base showing the terminals.

Fig. V is a detail perspective view of the contact plate, and

Fig. VI is a view showing the various electrical circuits and connections.

In the drawings, similar reference numerals refer to similar parts throughout the several views, and the sectional views are taken looking in the direction of the arrows at the ends of the section lines.

As illustrated, particularly in Fig. II, the base plate has mounted thereon, a U-shaped strip 1 of soft iron which is adapted to receive the electro-magnet 2 and which is insulated from the base by means of the fibre plates 3 and 4 and held in place by the core rivet 5. The end 6 of the strip is bent outwardly and the thin metal strip 7 and leaf spring 8 riveted thereto.

Intermediate the ends of the U-shaped strip 1 is placed the armature 9 of the electro-magnet, which consists of a flat plate of soft iron with one end riveted to the metal strip 7, and the other end narrowed as at 10, to form a base for one of the silvered contact points 11. In the body of the armature plate, a tongue 12 is struck out under which the terminal of the spring 8 is seated, normally forcing the armature outwardly.

An L-shaped plate 13 is attached to the U-strip 1, through insulation plates 14 and 15 by means of a screw 16. On the outwardly extending arm of the plate, a second silvered contact 17 is secured, which is adapted to contact with the first named contact plate when the armature is depressed.

Fastened also to the U-shaped strip 1 is a small plate 18 of non-magnetic material, such as brass, which has its upper end extending above the U-strip end, and terminating in a T-shaped head 19. A T-shaped slot 20 is cut in the armature 9 at a point adjacent the head 19, and in the wide end of which slot the head of the T is inserted and bent into the narrowed portion, thereby affording a limiting stop for the outward movement of the armature.

The electro-magnet 2 has a core of soft iron about which two coils of insulated wire are wound, one of large size and relatively few turns, forming the series coil in the charging circuit, and the other of small size and having a relatively large number of turns, forming a shunt coil in the generator circuit. The series coil has one end soldered on the L-plate 13 at 21, and the other end is brought out through the insulation plate in the base and soldered to the terminal 22.

From the L-plate the series circuit passes through the contact points 11 and 17, the armature 9, U-strip 1, rivet 5 connecting plate 23 to the base terminal 24. The shunt 5 coil has one end soldered to the base plate, forming a ground therewith, and the other end soldered on the series terminal 24. The iron magnetic circuit is preferably copper plated to prevent oxidation, and the whole 10 is enclosed in a sheet metal casing, the lower edges of which fit closely over the base sides, and are secured thereto.

The operation of the device is as follows: Normally, the series circuit is broken at the 15 contact points, thus preventing current discharge from the battery. When the engine is started, the generator voltage increases rapidly, forcing increasing current through the shunt coil of the electro-magnet. Owing to the iron circuit, the magnetic flux may pass from the core through either side 20 25 or 26, and consequently the arms of the U-strip 1 may be made of smaller dimensions than would be possible if one arm only were 25 used as a conducting path, inasmuch as a single arm of the same dimensions would become saturated before the point had been reached for the contacts to close. When the voltage due to the increasing speed of the 30 generator has become slightly greater than the battery voltage, the contacts 11 and 17 will close, and current will flow into the battery to charge it. When the engine slows down, the combined series and shunt currents 35 maintain the contacts in closed position to a voltage point below that at which contact was made by the shunt coil alone, so that a small reverse current will flow through the series winding. Chattering of 40 the contacts is thereby prevented.

It has already been noted that two magnetic paths 25 and 26 are provided in the electro-magnet. The reluctance of path 25 is only slightly greater than path 26 when 45 the armature is attracted as the air gap at the fulcrum end of the armature is slightly greater than that at the contact end, and in consequence, at the moment of break at the contacts, the magnetic flux through the path 50 26 is readily shifted to the path 25 of approximately equivalent reluctance, thereby permitting a quick break at the contact points with a corresponding decrease in the arcing effects.

It should be noted that the structure is exceeding compact in form, has comparatively few detachable parts, thus making the cut-out of great value where economy of space and weight and solid structure are essential.

I am aware that the particular embodiment of my invention, herein shown and described, is susceptible of considerable variation without departing from the spirit of 55 the invention, and, therefore, I desire to

claim the same broadly, as well as specifically, as indicated by the appended claims.

Having thus described my invention, what I claim as new and desire to secure by Letters Patent, is:

1. In an electro-magnetic cut-out, the combination of a metal base; a U-shaped iron strip attached thereto and insulated therefrom; an electro-magnet having a core within said strip; an armature having an opening therein attached to an arm of said U-shaped strip, said armature carrying a contact plate; a second contact plate attached to, and insulated from, the other end of said U-shaped strip; said electro-magnet 70 75 adapted when energized to cause said contact plates to close; means normally retaining the contact plates in disengagement; and additional means carried by the U-shaped strip and projecting thru the opening in the armature for limiting the distance of separation of the contact plates.

2. In an electro-magnetic cut-out, the combination of a core; a plurality of solenoids surrounding said core, comprising a series coil and a shunt coil; a U-shaped iron strip positioned about said solenoids; a contact plate on one arm of said strip, insulated therefrom, and in series with the series coil; an armature carrying a second contact plate 90 95 secured to the other arm of said strip; means for normally holding the armature away from said solenoid, and the contact plates in disengagement; said shunt coil when energized being adapted to close an electrical circuit through the contacts, the flux of said shunt coil following a magnetic circuit through each arm of the U-shaped strip and the said armature.

3. In an electro-magnetic cut-out, the combination of a core; a plurality of solenoids surrounding said core, comprising a series coil and a shunt coil; a U-shaped iron strip positioned about said solenoids; a contact plate on one arm of said strip, insulated therefrom, and in series with the series coil; an armature carrying a second contact plate secured to the other arm of said strip; means for normally holding the contact plates in disengagement; said shunt coil 105 110 115 when energized being adapted to close an electrical circuit through the contacts, armature, and one arm of the U-shaped strip, and to close a magnetic circuit through the armature and each arm of the U-shaped strip, the reluctances of said magnetic circuits being approximately equal when the contacts are closed and the reluctance of the magnetic circuit thru the arm carrying the contact plate being greater than the reluctance of the magnetic circuit thru the other arm when the contacts are open.

4. In an electro-magnetic cut-out, the combination of a core, a coil thereon, a magnetic member at one end thereof having an 120 125 130

- arm extending along each side thereof, an armature at the opposite end of said coil, means for securing one end of said armature to one of said arms, a contact carried by 5 said other arm, a co-operating contact carried by the adjacent end of said armature, said magnetic member and said armature providing a pair of return paths for the flux of said coil.
- 10 5. In an electro-magnetic cut-out, the combination of a core, a coil thereon, a magnetic member having portions extending across one end and up each side thereof, an armature flexibly secured to one of said side 15 portions and extending in proximity to each of said side portions, a stationary contact, a movable contact carried by said armature and means secured to the other of said side portions for limiting the movement of said 20 armature away from said coil.
6. In an electro-magnetic cut-out, the combination of a core, a coil thereon, a magnetic member having portions extending across one end and along each side thereof,
- an armature flexibly secured to one of said side portions and magnetically related to both of said side portions, a contact member secured to the outer face of the other of said portions having an outwardly extending contact arm, said armature having an outwardly extending portion provided with a contact point to co-operate with said contact arm.
7. In an electro-magnetic cut-out, the combination of a base, a substantially U-shaped magnetic strip secured to and insulated from said base, an electro-magnet positioned within said U-shaped strip, an armature for said magnet substantially bridging the arms of said strip and a flat spring connecting said armature to one of said arms for retracting the armature, a stationary contact member insulated from said strip and a co-operating contact member carried by said armature.

In testimony whereof I affix my signature.

CLARENCE F. GILCHRIST.
